UNITED STATES PATENT OFFICE.

FRANK J. DIACONT, OF PROVIDENCE, RHODE ISLAND, ASSIGNOR TO THE
WAITE, THRESHER COMPANY, OF SAME PLACE.

DESIGN FOR A HANDLE FOR BUTTON-HOOKS OR SIMILAR ARTICLES.

SPECIFICATION forming part of Design No. 32,987, dated July 24, 1900.

Application filed June 15, 1900. Serial No. 20,466. Term of patent 34 years.

To all whom it may concern:

Be it known that I, FRANK J. DIACONT, a citizen of the United States, residing at Providence, in the State of Rhode Island, have invented and produced a new and original Design for the Handle of a Button-Hook or Similar Article, of which the following is a specification, reference being had to the accompanying drawing, forming a part thereof.

5 The figure represents a plan view of the handle of a button-hook, showing my new design.

As shown in the drawing, the leading or material feature of my design consists of a cir-

cular bead *a*, the leaves *b b*, the represented 5 rosebuds *c, d*, and *e*, and the represented roses *f, g*, and *h*.

Having described my invention, what I claim as new, and desire to secure by Letters Patent, is—

20 The design for the handle of a button-hook or similar article, as herein shown and described.

FRANK J. DIACONT.
